W. R. CHANDLER,
RAILWAY BRAKE,
APPLICATION FILED JAN. 16, 1917.

1,229,229.

Patented June 12, 1917.

UNITED STATES PATENT OFFICE.

WILLARD R. CHANDLER, OF SUMTER, SOUTH CAROLINA.

RAILWAY-BRAKE.

1,229,229.

Specification of Letters Patent. Patented June 12, 1917.

Application filed January 16, 1917. Serial No. 142,686.

To all whom it may concern:

Be it known that I, WILLARD R. CHANDLER, a citizen of the United States of America, residing at Sumter, in the county 5 of Sumter and State of South Carolina, have invented certain new and useful Improvements in Railway-Brakes, of which the following is a specification.

The present invention relates to improvements in railway brakes, and is designed especially to improve the construction of the 10 brake shoe and brake head in certain particulars for the purpose of prolonging the life of the brake shoe and rendering impossible the falling to the track of parts of the shoe should it become broken in any way. Many accidents, with consequent loss of life 15 and damage or breakage of parts, are frequently caused on railroads by the falling 20 to the railroad track of a broken brake shoe or part of the shoe and consequent derailment of a car when its wheels pass over the obstruction. By the utilization of my invention, the durability of the brake shoe is 25 enhanced and the possibility of parts of a broken shoe falling to the ground is practically eliminated.

In the accompanying drawings I have 30 illustrated one complete example of the physical embodiment of my invention constructed and arranged according to the best mode I have so far devised for the practical application of the principles of my invention.

35 Figure 1 is a side view of a brake according to my invention, showing a car wheel in dotted lines, and the brake hanger or supporting strap, together with the end of the brake beam to which the head is attached.

40 Fig. 2 is a sectional view of the brake shoe illustrating the steel backing members of the shoe.

Fig. 3 is a perspective view of the brake 45 head.

Fig. 4 is a detail perspective view of one 50 of the duplex steel backing plates.

The brake itself is of the proper size and shape to conform to the standard required by the M. C. B. and embodies the customary 55 members indicated as the head 1 and the shoe 2, the former being of cast metal and formed with a projecting lateral lug forming a strengthening bridge or brace 3 while the central projecting lug 4 of the head is 60 transversely perforated at 5 to permit the

brake being supported on the brake beam 6, which preferably is round. The brake is adjustable on the beam and to hold the former in fixed position on the latter I employ a set bolt 7. Located centrally of the 65 head and opening at the front thereof is a mortise 8 partly closed at one side of the head by the bridge 3 and extending backward in the head to open outwardly into extension 9 thus forming a T-shaped mortise, open at both ends except, as before stated, for the bridge 3.

The mortise is adapted to accommodate the tenon 10 of the shoe which is located centrally thereof and projects backward 70 therefrom and is adapted to slide neatly into the mortise while an opening 11 in the tenon is provided for the bolt 12 for attaching the straps 13, one at each side of the shoe for suspending the brake.

To strengthen the brake shoe I employ a 75 pair of steel backing plates as 14 and 15 which are embedded in the metal of the shoe and cast therein above and below the center of the tenon.

These duplex plates each have a bent inner end 16 which terminates in a lug 17 formed by bending over the extreme end of the plate and crimping it or clamping it into a guide lug which projects from the 80 tenon at its corners and these two lugs are adapted to fit neatly into the extension 9 of the mortise in the head. At the opposite ends of the steel backing plates another angular flange 18 is provided complementary 85 to and embedded in the lugs 18' of the shoe proper. Each plate is formed with an extension 19 which is provided by stamping a hole or opening 20 and the extension projects on a line with the body of the plate at 90 an angle to the flange 18. Together with the two openings 21 21 in the plate or backing strip the opening or slot 20 provides for an interlocking key passing through the plate and joining the metal at opposite sides 100 of the plate.

Should the upper or lower portion of the shoe break it will be seen that the steel plates will hold the cracked or broken parts from falling, and one of the special features of 105 the invention resides in the use of the two plates, instead of one extending throughout the entire length of the shoe. The short back strips or plates permit expansion and contraction of the cast metal of the shoe 110

without breaking or cracking. The bent ends 17 of the steel plates or backing strips as will be seen are strengthened by being bent back upon themselves thus providing a rigid projecting lug at the corners of the lug 10. As before stated, the steel backs or plates are cast in the cast metal of the shoe when the latter is being molded.

What I claim is:—

- 10 1. The combination with a brake head having a T-slot therein, of a brake shoe formed with a corresponding T-lug, said lug having a pair of backing plates em-

bedded therein and each plate having a projecting end forming part of the T-lug.

2. The combination with a brake head having a T-slot and a bridge thereacross, of a brake shoe formed with a corresponding T-lug, said shoe having a pair of disconnected backing plates therein formed with interlocking openings for keys of cast metal, and the ends of said plates projecting from the shoe to form part of the T-lug.

In testimony whereof I affix my signature.

WILLARD R. CHANDLER.
